SIGN COMPOSING MEANS

William Henry Rogers, Washington, D. C.

Application December 23, 1937, Serial No. 181,418

5 Claims. (Cl. 95—85)

This invention relates to the composition of characters and more particularly to individual character units bearing indicia or signs such as alphabetical characters, numerals, symbols and the like and arranging of the said units to form words, sentences, ornamental designs or other types of composition.

Heretofore, individual alphabetical and other characters have been placed on supporting members to hold them for the purpose of forming units capable of being arranged one with another for producing designs and composition. The composition of characters is transferred to another support by methods well known in the art.

One well known method of transfer is printing from characters commonly known as "type." In this method a rectangular prismatic shaped body of metal is constructed to hold the raised printable character. A group of such type characters are correctly positioned in combination with each other so that the indicia may be printed onto another surface by the use of printing ink. This method of printing from metal type is so well known it needs no further explanation.

Another well known method of printing which is now extensively used in the art involves the use of plates. However, during the preparation of such printing plates, individual metal type units with raised printable characters are extensively used to form the design or composition which is applied to the printing plates.

In such instances, after the arrangement of type is completed, it is usual to place the composed type in some form of a printing press, apply ink to the face of the raised characters, and make a print on to paper or other suitable material. The design of the arranged characters thus printed on another support which is composed of sheet material is conveniently handled and can be placed before a camera and photographed to copy the characters thereon. The photograph is then used to produce the printable image on a printing plate.

Another method of arranging printable characters suitable for printing from metal plates is to use individual characters on units of sheet material. Usually these units are separately placed and fastened to a paper or card background in order to hold them so that they may be photographed on to sensitized metal surfaces for the purpose of forming printing plates. The advantages to be derived by the use of design characters on flat sheet material as distinguished from the usual raised metal type become ap-

parent when it is taken into consideration that it is necessary to transfer the design supported by the metal type to a flat sheet material such as paper by the use of ink and a printing press before it can be used for many of the photo-reproduction methods. The use of metal type in such processes consumes unnecessary time and labor and requires expensive machinery and metallic type units without which good printing cannot be produced.

Prior to this invention, suggestions have been made concerning the use of characters printed on sheet material in unit form although all of the units thus far proposed require much time and skill in order to use them in a satisfactory manner. It has been found to be extremely difficult to space correctly the individual characters which have heretofore been suggested and to maintain them in alignment especially when composing with small-sized letters. Prior to this invention specially designed structures have been found necessary to assist in the arrangement of the units and to hold them in aligned relation to each other. Such spacing and holding structures have taken the form of separate and independent devices which are in no way a part of the unit. The use of separate aligning devices is objectionable since additional means must be handled and their use becomes particularly inconvenient in composing a plurality of characters.

The present invention has for its purpose the provisions of improved character or composing unit structure and methods of use and therefore an object of this invention is to provide improved means whereby the difficulties pertaining to composition by composing units formed on sheet material are removed.

An object of this invention is to provide an improved means of assembling, spacing, holding, aligning and fastening together individual character composing units bearing alphabetical, numerical and ornamental indicia for the purpose of forming words, sentences and ornamental designs suitable for photo-mechanical reproduction.

Another object of this invention is to provide an improved method of holding together or interlocking units of sheet material such as paper, card, sheet metal, rubber, Cellophane or other cellulose substances with letters of the alphabet or other signs printed or in any other manner placed thereon so that the signs can be copied and then used for making intelligible compositions.

Another object of this invention is to provide an improved method of holding together units of

sheet material with letters of the alphabet or other signs printed or in any other way placed thereon so that the characters can be copied and used in making display signs, motion picture titles, name plates and the like.

Another object of this invention is to provide an improved means for holding together separate units of sheet material bearing indicia or signs in properly spaced relationship so that when 10 photographed by a suitable camera onto printing plates they can be used for printing by methods known in the art.

Another object of this invention is to provide an improved means for composing printable characters for making printing plates by photo-engraving or other photo-methods used in the graphic arts.

A further object of my invention is to provide improved methods and means for producing 20 "copy" or reproduction sheets of alphabetical, numerical and ornamental characters in adjusted alignment from which a photograph can be made and used for signs, advertising display, "copy" for photo-mechanical reproduction and photographic models.

A further object of this invention is to provide improved methods and means for the fabrication of a character-bearing or composing unit of sheet material which can be grouped with other 30 character-bearing units to form lines of composed indicia suitable for use with known methods of printing by photography or photographic, mechanical or chemical transfer, the means for holding, spacing, aligning and fastening one unit 35 with another being incorporated with and a part of the unit itself.

A further object of this invention is to provide improved means and a method of assembling, spacing, holding, aligning and fastening together 40 alphabetical characters or other signs of a printable nature to form words, sentences and ornamental designs or other indicia suitable for use as printing plates.

A further object of this invention is to provide 45 an improved composing unit having a sign or an area, a sign supporting medium, a handle portion and binary means positioned in spaced relationship with the particular sign or character for the purpose of spacing the character or sign 50 from the sign of another composing unit when a plurality of units are overlapped in staggered relationship.

Other objects of my invention will be apparent 55 from the following description and the accompanying drawings referred to herein wherein:

Fig. 1 discloses a front view of an improved composing unit;

Fig. 2 discloses an assembly of a plurality of 60 the improved composing units in overlapped and staggered relationship;

Fig. 3 discloses a side view of the overlapped and staggered composing units;

Fig. 4 discloses a front view of an improved 65 composing unit designed to be aligned in a curved line of composition;

Fig. 5 discloses an assembly of a plurality of the composing units positioned on a curved line of composition;

Fig. 6 discloses an assembly of the improved 70 composing units secured in alignment by hand;

Figs. 7, 11, 17, 20, 23 and 25 disclose a front view of improved composing units having projecting means for aiding in aligning a plurality of 75 the units;

Fig. 8 discloses a side view of the improved composing unit shown in Fig. 7;

Figs. 9, 13, 19, 22, 24, 26, 27 disclose front views of the assembly of a plurality of improved composing units having projecting spacing means; 5

Figs. 3, 10, 15 and 16 disclose side views of assemblies of a plurality of composing units;

Fig. 12 discloses a side view of the improved composing unit shown in Fig. 11;

Fig. 14 discloses a rear view of the assembly 10 shown in Fig. 13;

Fig. 18 discloses a section taken on line 18-18 of Fig. 17;

Fig. 21 discloses a section taken on line 21-21 of Fig. 20;

Figs. 28 and 31 disclose front views of improved composing units provided with sign spacing indicating means;

Figs. 29, 32, 33 and 35 disclose front views of the assembly of a plurality of improved composing 20 units having sign spacing indicating means;

Figs. 30 and 34 disclose front views of improved composing units provided with sign spacing indicating means and attachable and detachable arresting and interlocking means; 25

Figs. 36 and 37 disclose side views of a plurality of overlapped composing units from which the handle portions have been removed;

Figs. 38 and 39 disclose signs positioned on an individual background; 30

Figs. 40, 41 and 42 disclose the details of a sign having a raised surface;

Fig. 43 discloses an improved composing unit having an area for mounting a sign having an individual background; 35

Figs. 44, 45 and 46 disclose various types and mounting of signs on individual backgrounds;

Fig. 47 discloses an end view of a plurality of overlapped lines of composing units;

Fig. 48 discloses a front view of a plurality 40 of overlapped lines of composing units;

Fig. 49 discloses an improved composing unit for use with inclined signs; and

Fig. 50 discloses an individual character which is applicable to the improved composing units. 45

By referring to Fig. 1 an alphabetical character or other sign 10 is printed on or in some other way applied to the supporting member 11 which in this figure is shown to be a rectangular-shaped piece of sheet material. It will be noted that the supporting member 11 is relatively larger than the character 10 which it supports, the character or design which is in this instance a letter of the alphabet 10 being close to the edge 12 of the support 11. Only a small portion of 50 the support is used as a background for the character 10, the remaining portion being adapted to hold, align and space the character in relation to other characters on their respective supporting members, when placed together in an 55 overlapping position as is shown in Fig. 2. The character-bearing support 11 can be made of any suitable sheet material which may be opaque, transparent or semi-transparent as well as dark or light colored material. When the character 60 itself is dark, the portion of the support immediately under the character and acting as a background for it, is light-colored and can be opaque, transparent or semi-transparent, but when the character is of a light color the background portion is made of dark-colored material. White paper or card material can be used to construct the supporting members 11 with a black character printed or otherwise placed thereon, and it is within the contemplation of this invention 70

75

to employ black paper or card material with a white character similarly placed thereon. The relation of the color of the character to its background will thus be such that there will be sufficient contrast between the character and its supporting background to enable a copy to be made for printing purposes. When either the background or the sign is formed of transparent or translucent material, the composing unit may 10 be employed for contact or projection printing on photo-sensitized surfaces.

Paper and card material have been mentioned as suitable materials for the construction of the supporting members 11 upon which the character is held but I do not wish to limit myself to this material for sheet metal, Cellophane, cellulose acetate or other cellulose derivative, fibre sheet plastic, resinous material or other sheet-like materials can be used. I also contemplate 20 using two or more different materials and incorporating them together to form a character-bearing unit such, for example, as a unit having the body of the supporting member formed of one material, the face portion immediately underlying the character formed of a different material and the character formed of a material different from the other parts. This forms a unitary combination of different materials each of which is specially selected to function more efficiently 25 30 for the individual part of the composing unit for which it is employed.

Figs. 2 and 3 illustrate a plurality of individual character-bearing units which are positioned with other like units to form a word. It will be noted 35 that the character-bearing units 20 to 27, inclusive, are overlapped in staggered relationship and that the indicia area 15 is associated on a portion or adjacent to the portion of each of the members which is not in an overlapped relationship. 40 Each of the individual composing units which go to make up the word or sentence comprises a backing or supporting portion and a character or other sign indicia adjacent to one end of the backing member as is described. At least one 45 edge of the backing member is formed parallel to the orienting base of the character or indicia so that when a plurality of the units are placed in overlapped relationship with their edges placed in line, the characters on each of the individual 50 members will be correctly aligned to form the desired line of composition as is shown in Fig. 2. Fig. 6 discloses a plurality of the overlapped composing units formed in spaced and aligned order by orienting the units in the hand by means of 55 their elongated edges.

Each of the backing or supporting members 11 is of such width as to accommodate the size of characters or indicia which is desirable to use in the line of composition. The width of the 60 backing members is dependent upon the relative size of the characters and in addition, the backing member is of such length that when a plurality of character-bearing units are placed in overlapped and staggered relationship a portion of 65 each of the backing members of the units will be available for securing together the overlapped units. An important feature of this invention resides in the fact that the individual backing or supporting members of the units are of such 70 length that when they are grouped in overlapping relationship they will form an aligning means for positioning the characters in a line of composition.

The portion of each unit which is not in overlapped relationship is represented by reference

numerical 15 of Fig. 2 whereon is located the character designated by 16 or this area may be unoccupied if spacing units are desired. When the units are grouped as indicated in Fig. 3 the indicia on each of the units appears in a line 5 broadly designated by reference numeral 17 of Fig. 2. The direction of the line of composed characters described appears as a straight line. It is apparent that as many indicia containing or composing units as are needed may be grouped 10 together to make the line of composition of any desired length. Blank members may be inserted in the overlapped group of composing units in order to increase the space between the words and characters. The additional length of the 15 backing and supporting members of the units is provided for use in holding the units together which may be accomplished by holding the overlapped group of members in the hand until they are secured by the use of adhesive or other suitable means. 20

As is shown in Fig. 1 the alphabetical character or sign supporting member 11 is fabricated from sheet material and is of a rectangular shape having an edge cut on a straight line which serves 25 as a directionally-aligning means. Another important feature of my invention is the formation of the aligning means in the direction and parallel to the line of grouped character units which comprise the desired line of composition. Therefore, it will be apparent that if the line of characters, when grouped together to form words, sentences or other indicia, is required to be in a straight-lined direction, the aligning means will be a straight-lined aligning member. It is also 30 35 a part of this invention to use character-bearing units suitable for curved-line composition and for these units the aligning means comprises a curved-line aligning member fabricated on or in each unit parallel to the curved line of the desired line of composition. 40

The construction of a single unit having a curved aligning means is shown in Fig. 4 wherein 45 50 55 60 65 70 75 80 85 90 95 100 105 110 115 120 125 130 135 140 145 150 155 160 165 170 175 180 185 190 I form a new and useful holding, aligning and spacing member, which can be used alone as such, or have therewith incorporated other members for a like purpose. A directionally-lined member so constructed forms a holding, aligning and spacing means requiring no separate holding and aligning structure such as frames or other supports specially designed to hold the composing units in spaced and aligned relationship. My improved character-bearing unit is complete in itself having holding, spacing and aligning means in combination with and a part of the unit itself, suitable for forming lines of composed words, sentences or other indicia by using the hands alone, as is shown in Fig. 6. However, it is to be understood that the invention is not limited to this method of use and it is to be understood that mechanical or other devices can be used to place the composing units together without departing from the scope of this invention, as is defined in the claims.

The lengths of the aligning members vary according to the size of the character wherewith they are incorporated and also the length of the line of composition to be formed by the grouped character units. For a long line of composition I use a long aligning member, i. e. one having an elongated handle portion, and for a short line of composition, a member having a shorter handle portion is used. I do not limit myself to any maximum length for the member and the minimum length is governed by the fact that it will not effectively operate if too short and if the length of the aligning means is further shortened the character units could not be kept in the line of direction intended without resorting to other external aligning means than the hand in which they are held. Therefore, it will be clear that when this directionally-lined aligning means and the transferable design or alphabetical character are correctly coupled together by the supporting member a unit combination will be formed, for the purposes set forth.

In order that the character-bearing or composing units herein above described may be more easily positioned when being grouped together so that the characters thereon may be quickly, accurately and properly spaced with relation to each other to form lines of letters, words, sentences or other indicia, I use a spacing or stop means which is also a part of this invention. The stop means is placed on or is incorporated with the handle or other portion of the character-bearing unit as is indicated by the various modifications of the spacing devices shown in the drawings. The stops or sign space adjusting members herein described are essentially binary in that they have two parts with indicating properties which function together to indicate the outer boundaries of the area required to display the sign configuration when composed with other composing units in line formation. One part of the binary spacing means is adjusted to one edge of the space area occupied by the sign or other character or blank space and the other part of said binary spacing means is adjusted to the opposite edge of the said area. This combination of elements is adapted to indicate the position or arrest the movement of the overlapping adjacent composing units to produce correct spacing for sign configurations of various sizes like that which is required when alphabetical characters are arranged together to form words, sentences and the like.

The stop member designated by reference numeral 40 in Figs. 7, 8, 9 and 10 serves to space the character-bearing units 41 as they are placed in overlapping position so that the line of composition 42 formed by the characters 43 is properly spaced. The stop members 40 are pre-formed as shown in the drawings and can be lifted to project above the surface of the character-bearing units in the form of tongues or the like. The edge 44 of the composing unit opposite the handle portion 46 is placed in abutting relationship with the base of the tongue or projecting member, as is indicated by 45 in Fig. 10. By properly placing the location of the pre-formed tongue in respect to the particular size and character of the indicia or sign, an overlapped group of the units, when placed in abutting relationship, will form the desired line of composition.

Figs. 11, 12, 13, 14, 15 and 16 disclose a similar binary arrangement of tongue and abutting members. As will be observed, the tongue 50 is pre-formed in the handle portion 51 of the aligning and character-bearing units 52. In arranging a group of character-bearing units together, the tongue is lifted and the adjacent unit is allowed to slide between the lifted tongue and the material of the support from which it was formed till its movement is arrested and its edge 53 reaches the position 54 where the tongue is attached to its supporting member. The tongue portion also helps to hold one unit to another and if made of a substantial length such as is shown in the figures the units when grouped together will not easily slip over the stop members and cover up the character or the character area or the space area on the units. Fig. 16 discloses the tongues 50 bent back upon the units 52. This serves to fasten the units together more securely so that they will be maintained in properly aligned and spaced positions.

It is apparent that as many indicia containing members as are desirable may be grouped together to make the line of composition of a desired length. Blank members 47 and 56 may be inserted in the overlapped group so that a space will appear between the characters as is shown in Figs. 9 and 13. The blank spacing units are so constructed that greater spaces can be inserted between the characters when grouped together than that which can be produced by the character-bearing units themselves.

Figs. 17, 18 and 19 disclose a character-bearing unit 60 having a pressed or struck projection 61 positioned opposite the handle portion of the unit. Edge 62 of an overlapping composing unit is arrested by the stop or projection 61 as is represented by reference numeral 65, so that the character areas bearing characters 63 are properly exposed and the characters form an aligned and spaced group of signs. Figs. 20, 21 and 22 disclose a character-bearing or composing unit 70 having a projection 71 which may be formed integrally with the unit by moulding or the like or attached thereto by well known means. The projections are positioned on the backside of the handle portion of unit 70 and serve to arrest the edge 72 of an overlapping composing unit, as is represented in Fig. 22.

The binary arrangement of the spacing means disclosed above relative to Figs. 7 to 22, inclusive, comprises an arresting means associated with a unit which cooperates with an edge or other portion of a second unit. The modification disclosed in Figs. 23 to 27, inclusive, embodies a binary spacing arrangement which includes an

interlocking means in combination. As will be observed in Figs. 23 and 24 a tab or projection 80 is formed at one end 81 of a character-bearing unit 82. An aperture 83 is provided through 5 which a tab or projection of an overlapping unit may be positioned. When the tab is placed so that the edge 81 is adjacent the edge 86 of the aperture of an overlapping unit, the characters 10 84, character areas and blank spaces will be properly aligned and spaced to form a line of composition 85. A similar composing unit comprising a binary spacing and adjusting means is disclosed in Figs. 25 to 27, inclusive. In Fig. 25 a tab 90 is positioned adjacent the character-bearing area 91 of a composing unit 92. A series 15 of apertures 93 is positioned within the body of the composing unit and extend into the handle portion 94 of the unit 92. Figs. 26 and 27 disclose different ways of assembling a plurality 20 of the units disclosed in Fig. 25. As will be observed, the letters may be spaced various distances apart by inserting the tab 90 in the different apertures of the series 93. For example, 25 in Fig. 26, the letters 95 are spaced relatively close together by placing the tab in the aperture most closely positioned with respect to the character. In Fig. 27, the tab is placed in the aperture at the opposite end of the series which results in the characters of the line of composition 30 being spaced further apart. This broad means of adjusting the spacing is extremely useful for purposes of justifying the lines of composition and in addition serves as a means for interlocking the individual units in their adjusted positions. This interlocking spacing means also serves as another aligning means for the characters and may be used either with or without the handle portion for aligning a plurality 35 of the units.

40 In addition to the binary spacing and interlocking arrangements disclosed above, it frequently becomes necessary to employ visual indicating means for adjusting the spacing and alignment with great precision. For this reason, 45 it is convenient to employ reference indicia of a binary character which may take the form of visual indicators or apertures. Fig. 28 discloses a composing unit 100 having a series of parallel reference lines or elements 101 positioned on the 50 bottom thereof which may extend from beneath the character in the character area into the handle portion. By placing an edge 102 of an overlapping unit in contact with a selected reference line the characters may be properly 55 aligned and spaced, as is disclosed in Fig. 29. Due to the fact that the reference lines extend into the character area as well as the handle portion, they may be used for justifying letter signs which appear in the line of composition 60 which would be otherwise difficult to space with precision. A somewhat similar visual indicating arrangement is disclosed in Figs. 30 to 33, inclusive, in which an aperture 110 formed in composing units 111 is matched or registered with 65 one of a plurality of similar apertures disclosed in Figs. 30 and 32 or with reference indicators 112 disclosed in Figs. 31 and 33, which may take the form of dots, squares or other marks. In case two or more units are overlapped, as is 70 shown in Figs. 32 and 33, the characters and character areas are properly aligned and spaced so that the line of composition will have the correct justification. Figs. 34 and 35 disclose similar use of apertures for spacing and justification 75 except the apertures 114 of composing unit 115

are placed in the handle portion of the composing units. An important feature of this invention comprises the employment of securing means in the matched or registering apertures to hold the overlapping units in place. Figs. 30 5 and 34 disclose securing devices, such as attachable and detachable pins 116, or the like, which can be inserted through the matched apertures for this purpose. As is indicated, the shank portions 117 of the securing devices may be square 10 or round or have other cross-sectional shape to fit the particular apertures through which it is passed for the purpose of arresting and interlocking the composing units in proper spaced relationship. 15

The blank spacing units represented by 47, 56 and 87 are formed in the same manner and are aligned and spaced in the same way that the character-bearing composing units are employed, the only difference being that the character or 20 body area is left blank.

In summary it will be observed that the character-bearing and spacing members may assume a number of different shapes and sizes and may be placed on the backing or supporting material 25 in various ways. Also, it will be seen that the stop members may be made of rectangular, round or other shaped pieces of metal, paper, fibre or other materials or may be pressed from the backing material itself. It is also within the contemplation of this invention to form the stop members from the backing material itself by cutting slots, slits or other formations and bending the material to intersect the plane of the adjacent indicia-bearing unit. It is also within 30 the conception of this invention to employ appropriate stop or spacing members either formed integrally with the indicia-bearing units or separately thereof which will serve to space and hold securely the adjacent units in aligned position. 40 As is indicated in the drawings, the stop members may be placed on the front or back of the sheet material in various positions such as adjacent to the edges of the indicia-bearing units or within the body portion of the indicia-bearing units. It is also within the contemplation of this invention to provide apertures and cavities and also interlocking means which may be 45 matched to serve in holding the units together and holding them in spaced relationship. 50

Another important feature of this invention is a means for detaching the characters from their aligning and space adjusting means. After the characters on a group of units have been placed together in an overlapping position and correctly spaced and aligned with relation to each other they can, if desired, be permanently fastened together. This can be done with adhesive or other known fastening means for sheet material. Adhesive substances can be applied to any portion of the overlapping area, such, for example, as the area designated by reference numeral 120 in Figs. 1 and 2, as the units are being placed in the composing of words or other indicia or the overlapping portion of the units can have an adhesive substance placed thereon previous to its being grouped together with other units. The units can also be fastened together by stapling or other mechanical fastening devices and a portion of the overlapping sections 60 can be reserved for this purpose. 65

When the characters are permanently fastened by one or more of the above described methods only a small portion of the composing unit is needed to support them, for which reason 70 75

the remainder of the unit with the aligning and adjusting means is of no further use. It is within the contemplation of this invention to remove the unneeded portion by tearing, shearing or other means of detaching and reference lines may be used to guide the detaching operation. It has been found convenient to employ lines of weakness for the purpose of aiding in the detaching of the unneeded portion after the characters have been permanently fastened together in alignment. It is contemplated that the lines of weakness may be placed at any desirable place. The use of vertically directed lines of weakness for detaching the handle portion of a composing unit is disclosed in Figs. 1, 2, 3, 11, 13, 14, 20 and 22. Reference numeral 130 indicates a line of weakness, such, for example, as a line of perforations. Figs. 36 and 37 represent a group of overlapped composing units from which the handle portions have been detached. Horizontally directed lines of weakness 131 may be employed for use in detaching the portion of the composing unit which supports the binary spacing members as is shown in Figs. 17, 19, 28, 29, 31 and 33. The composing units may be used without either the vertically or horizontally directed lines of weakness or they may have either the vertical or horizontal lines or a combination of both.

30 In references to the indicia placed in the character-bearing area of the composing units, Fig. 50 illustrates an independent surface character without supporting structure excepting the material for making the character visible. A suitable visible material can be "printing ink" or "transfer ink" or any visible material that can be transferred completely or in part from one support to another without destroying the character's original contour. Figs. 40 and 41 illustrate 40 an independent character having a raised surface which is also within the contemplation of this invention. A composing unit formed with raised surfaces can be employed as a type unit and may be used in printing operations together with printing ink, inked sheets, inked ribbons or the like. Fig. 42 discloses the relief character mounted on a suitable background. Figs. 38 and 39 show characters or signs 140 formed on a sheet supporting background 141 separately constructed and adapted for attachment to the area provided on the surface of the composing units. The sheet supporting background 141 may be made of paper, card, metal, cellulose derivatives, sheet plastic material, rubber, Cellophane or any like material, opaque or translucent; and it can also be a decalcomania. Figs. 44, 45 and 46 are 55 illustrative of some of the various positions and arrangements of a sign on the background. Fig. 46 represents positioning the sign in reverse order for producing positive copy by photography or other printing means. Fig. 49 discloses a composing unit suitable for composing a line of inclined signs. This unit is similar to the others except the edge adjacent the inclined sign is 60 formed at an angle.

The characters 140 and background 141, as shown in Figs. 38 and 39, may be mounted in the character area of the composing units designed to accommodate the characters either before or 70 after the blank composing units are fabricated.

Furthermore, the characters together with their backgrounds may be removed and transferred to another supporting surface either individually or collectively after the line of composition has been completed. Fig. 43 shows a blank composing unit 5 having a handle portion and a character area in which the prefabricated characters may be placed. It will be understood that the arrangement of the binary spacing means will vary with the particular area required for the different 10 characters as well as their size and shape.

The composing units made in accordance with this invention may be used in many different ways. The individual units or composed lines of the character-bearing units may be used as 15 display signs or they can be transferred to another supporting surface by photographic means. In addition, the lines of composition may be employed as printing plates when the characters are formed with transfer inks or when 20 printing ink is applied to the lines of composition are formed with characters having raised surfaces. When lines of composition are formed with composing units having removable characters, the characters may be removed and transferred to a different supporting surface and the transferred lines of composition may then be 25 used for purposes requiring composed letters or signs. A plurality of composed lines may be overlapped in the manner shown by Fig. 47 to 30 form a composite sign such as is shown in Fig. 48.

Various modifications and embodiments of my invention will be apparent to those skilled in the art, and it is my desire that the appended claims shall cover all modifications and arrangements 35 which come within the scope and spirit of my invention.

What I claim and desire to protect by Letters Patent is:

1. A flat composing unit formed of sheet-like material suitable for use in forming composition comprising a sign, a sign supporting area, a handle portion, a projecting member and a plurality of apertures formed in said composing unit each of which is adapted to receive the projecting member of an adjacent unit whereby the units may be adjustably spaced. 40
2. A flat composing unit formed of sheet-like material suitable for use in forming compositions comprising a sign, a binary sign spacing arrangement comprising apertures positioned in spaced relationship to said sign and members adapted to be inserted and removed from the matched apertures of two overlapping composing units. 50
3. A flat sheet-like composing unit suitable for photographic reproduction comprising a sign, a sign area, a handle portion and a sign-spacing means in the form of an element projecting from the flat sheet surface of the said composing unit. 55
4. A flat sheet-like composing unit comprising a sign portion, an extending handle portion, sign-spacing members comprising marks and apertures fabricated in and on said extending handle portions. 60
5. A flat sheet-like composing unit of oblong 65 shape, suitable for photographic reproduction, comprising a sign, a sign portion, an extending handle portion, and sign spacing tabs and slots formed from said handle portion.

WILLIAM HENRY ROGERS. 70
